(57) **CLAIM**

The ornamental design for an electric bicycle, as shown and described.

DESCRIPTION

FIG. 1 is a perspective view of an electric bicycle embodying our new design;

FIG. 2 is a partial and enlarged perspective view thereof, where the area of enlargement is indicated as area "2" in FIG. 1;

FIG. 3 is a partial and enlarged perspective view thereof, where the area of enlargement is indicated as area "3" in FIG. 1;

FIG. 4 is a front elevation view thereof;

FIG. 5 is a top plan view thereof;

FIG. 6 is a rear elevation view thereof;

FIG. 7 is a right side elevation view thereof; and,

FIG. 8 is a left side elevation view thereof.

The broken lines in the drawings are provided for the purpose of illustrating the areas of enlargements and do not form part of the claimed design. The broken lines do not show structure or environment and only show the region for which the enlargements are taken.
